LPA(57) **CLAIM**

The ornamental design for a "carafe assembly," as shown and described.

DESCRIPTION

FIG. 1 is a front view of the carafe assembly, wherein the rear view is the same as the front view;

FIG. 2 is a right side view of the carafe assembly illustrated in FIG. 1, wherein the left side view is the same as the right side view;

FIG. 3 is a front left side slightly downward-looking perspective view of FIG. 1;

FIG. 4 is a top view thereof; and,

FIG. 5 is a bottom view thereof.

The broken line areas showing portions of the carafe assembly form no part of the claimed design.
